Westinghouse Electric & Manufacturing Com-
pany, a corporation of Pennsylvania

Application July 31, 1936, Serial No. 64,150

Term of patent 14 years

To all whom it may concern:

Be it known that I, Ralph E. Kruck, a citizen
of the United States, residing at Springfield, in
the county of Hampden and State of Massachusetts,
have invented a new, original, and ornamental
Design for a Combined Electric Food Mixer
and Fruit Juicer, of which the following is a spec-
ification, reference being had to the accompanying
drawing, forming a part thereof, in which:

Figure 1 is a perspective view, taken from the
front and one side of the combined electric food

mixer and fruit juicer, showing my new design,
the concealed end of the horizontal axis motor
being like the end illustrated; and

Figure 2 is a view in rear elevation of the com-
bined electric food mixer and fruit juicer.

I claim:

The ornamental design for a combined electric
food mixer and fruit juicer, substantially as
shown, and described.
